UNITED STATES PATENT OFFICE.

CHARLES N. ANTHONY, OF ORGAN, TERRITORY OF NEW MEXICO.

CRUCIBLE ASSAY-FURNACE.

SPECIFICATION forming part of Letters Patent No. 743,214, dated November 3, 1903.

Application filed August 1, 1902. Serial No. 117,973. (No model.)

To all whom it may concern:

Be it known that I, CHARLES N. ANTHONY, a citizen of the United States, residing at Organ, in the county of Doña Ana and Territory of New Mexico, have invented new and useful Improvements in Crucible Assay-Furnaces, of which the following is a specification.

This invention is an improvement in that class of crucible assay-furnaces adapted to be heated by a jet of burning gas or gasoline forced under pressure by a suitable burner or blowpipe into the furnace, its objects being to effect improvements in the construction of the furnace whereby combustion of the gas or gasoline-vapor is promoted in the interior of the furnace, whereby the furnace is adapted to be more rapidly and thoroughly heated than heretofore, whereby an economy of fuel is effected, and whereby the furnace is adapted to be heated to a uniform degree throughout its entire interior extent.

With these and other objects in view the invention consists in the construction of a crucible assay-furnace with a plurality of communicating chambers or bowls having outwardly and upwardly inclined sides.

The invention further consists in the construction of a crucible assay-furnace with inwardly-projecting baffles in its opposing sides, forming a plurality of communicating chambers intermediate the blast opening and flue or chimney.

The invention further consists in the construction of a crucible assay-furnace with a chamber or bowl having its sides concaved longitudinally and upwardly and outwardly inclined.

The invention further consists in the construction of a crucible assay-furnace with a plurality of communicating chambers intermediate the blast opening and flue or chimney and diminishing in size toward the latter.

The invention further consists in the peculiar construction of the furnace hereinafter specified, and set forth in the appended claims.

In the accompanying drawings, which form part of this specification, Figure 1 is a vertical longitudinal central sectional view of a crucible assay-furnace constructed in accordance with this invention. Fig. 2 is a top plan view of the same, and Fig. 3 is a vertical

transverse sectional view taken on a plane indicated by the line xx of Fig. 2.

The furnace A is in practice made of fire-clay or other suitable material and may be of any suitable dimensions and proportions with respect to its several parts. At the front end of the furnace is the blast-opening a , through which the jet or blast of burning gas or gasoline-vapor is discharged from a suitable burner or blowpipe into the interior of the furnace. At the rear of the furnace is the upwardly-extending flue or chimney b . Intermediate the blast opening and flue or chimney are a plurality of communicating chambers or bowls, in which the charged crucibles are placed, so that their contents may be fused or melted by the heat of the blast, the furnace being provided with the usual cover c , which is here shown as a number of separately-removable slabs of fire-clay or other suitable material, which enable the interior of the furnace and the contents of the crucibles to be inspected.

The chamber or bowl d next the front end of the furnace is wider than the chamber or bowl e at the rear end thereof. These chambers communicate with each other at f and are partly separated from each other by inwardly-projecting baffles g , which extend from opposite sides of the furnace and serve to choke or partly obstruct the passage f between the two chambers. The sides of the latter are curved or concaved longitudinally to form the said baffles, as shown in Fig. 2, and are also inclined upwardly and outwardly, as shown in Fig. 3, so that the said chambers have their upper open sides wider than their lower sides. By this construction of the sides of the chambers the heat is deflected and distributed uniformly throughout the chambers, so that the same are heated to the same degree at all points. The chamber e at the rear end of the furnace is of less width than the chamber d at the front end thereof.

The heat of the blast diminishes as it recedes from the front end of the furnace; but by narrowing the rear chamber, constructing the walls of the chamber d so that heat will be deflected therefrom into the rear chamber, and by constructing the walls of the latter in the manner hereinbefore described both chambers become heated to the same de-

gree. Furthermore, this construction of the walls of the chambers and the provision of the baffles retards the passage of the blast through the furnace and increases the area of the 5 walls or sides of the chambers against which the blast of flame impinges when the crucibles are in the furnace, thereby promoting the combustion of the gases or vapors during their passage through the furnace, so that the 10 gases or vapors are consumed therein and are not allowed to escape unconsumed through the flue or chimney, thereby causing the chambers and the crucibles therein to be the more thoroughly heated in less time and enabling an economy of fuel to be effected, as 15 will be understood. Another advantage gained by this construction of the furnace is that by reason of the uniform temperature to which the same is heated the contents of all 20 the crucibles therein are fused alike and the accuracy of the assays increased.

On the floor of the furnace I place an absorbent bed of coarse and loose calcined fire-clay, (indicated at *h* in the drawings,) which 25 varies in depth according to the height or size of the crucibles. This bed enables the vertical space in the bowls or chambers to be contracted as may be required to secure the best results, affords a safe and clean rest or 30 support for the crucibles, and preserves the floor and sides of the furnace-chambers from the destructive action of the "fusions" spilled by the handling or breaking of the crucibles by accident. In a furnace of the ordinary 35 size the depth of the bed (which is preferably made of broken fire-brick about eight or ten mesh fine) is usually from one to two and one-half inches, being varied according to the height or size of the crucibles and, together 40 with the crucibles, which are indicated in dotted lines in the various figures of the drawings, varies the area or areas of the crucible chamber or chambers to the heating capacity of the burner or blowpipe employed in connection with the furnace, thus enabling the 45 best results to be obtained. The bottoms of the crucibles may be embedded in this bed to any desirable extent to prevent the crucibles from tipping. The covers *c* and the crucibles are handled by angled tongs when the 50 furnace is in use.

What is claimed as new, and is desired to be secured by Letters Patent, is—

1. A crucible assay-furnace having blast

and flue openings at opposite ends and inwardly-projecting upright baffles in its opposing sides, forming a plurality of communicating chambers intermediate the blast opening and flue, and also forming an opening therewith, said chambers coextensive in height 60 in width progressively toward the flue, substantially as described.

2. A crucible assay-furnace having blast and flue openings at opposite ends and inwardly-projecting upright baffles in its opposing sides, forming a plurality of communicating chambers intermediate the blast opening and flue, and also forming an opening between said chambers, coextensive in height 65 therewith, said chambers being diminished in width progressively toward the flue, substantially as described.

3. A crucible assay-furnace having blast 75 and flue openings at opposite ends and inwardly-projecting upright baffles in its opposing sides, forming a pair of communicating chambers intermediate the blast and flue openings and also forming an opening between said chambers, coextensive in height 80 therewith, the front chamber being wider than the rear chamber, and having its walls, near the blast-opening, disposed at such an angle as to deflect heat into the rear chamber, substantially as described.

4. A crucible assay-furnace having blast and flue openings at its respective front and rear ends, and inwardly-projecting upright baffles in its opposing sides, forming a pair 90 of communicating chambers intermediate the blast and flue openings and also forming an opening between said chambers, coextensive in height therewith, said front chamber being wider than the rear chamber and having 95 its walls near the blast-opening disposed at such an angle as to deflect heat into the rear chamber, and each of said chambers narrowing toward the flue-opening, substantially as described.

In testimony whereof I have signed my name to this specification in the presence of two subscribing witnesses.

CHARLES N. ANTHONY.
